[57] CLAIM

The ornamental design for a set of mouldings for furniture, as shown and described.

DESCRIPTION

FIG. 1 is a front, right side perspective view of a set of mouldings for furniture showing my new design, the left side being a mirror image thereof;

FIG. 2 is a front, left side perspective view of a second embodiment of the set of mouldings for furniture shown in FIG. 1;

FIG. 3 is a front, right side perspective view of FIG. 1 on a different casegood;

FIG. 4 is a front elevational view thereof;

FIG. 5 is a front, left side perspective view of a third embodiment of the set of mouldings for furniture shown in FIG. 1;

FIG. 6 is a front, left side perspective view of a fourth embodiment of the set of mouldings for furniture shown in FIG. 1;

FIG. 7 is a front, right side perspective view of a fifth embodiment of the set of mouldings for furniture shown in FIG. 1;

FIG. 8 is a front, left side perspective view of FIG. 6 on a different casegood; and,

FIG. 9 is an enlarged front elevational view of the bottom right corner of the moulding.

The broken lines shown on the top rear of each casegood indicate the boundary of the claimed design; the other broken lines shown throughout the views are for environmental purposes and form no part of the claimed design.
